(57) **CLAIM**

(21) Appl. No.: **29/137,661**

The ornamental design for a mouthpiece and collar for an
inhalation device, as shown and described.

(22) Filed: **Feb. 26, 2001**

DESCRIPTION

(30) **Foreign Application Priority Data**

Aug. 26, 2000 (GB) 2095344

FIG. 1 is a perspective view of a mouthpiece and collar for
an inhalation device showing our new design, with the collar
engaged. The broken lines showing is for illustrative pur-
poses only and forms no part of the claimed design.

(51) **LOC (7) Cl.** **29-02**

FIG. 2 is a perspective view thereof, with the collar disen-
gaged;

(52) **U.S. Cl.** **D24/110**

FIG. 3 is a front view thereof; and,

(58) **Field of Search** D24/110, 110.4,

FIG. 4 is a side view thereof.

D24/110.5; 128/200.23, 200.24, 200.16,
200.18, 200.14, 200.25, 203.23
